APPARATUS FOR THE PRODUCTION OF AIR FOAM AND AIR-FOAM FIRE-EXTINGUISHING INSTALLATIONS

Günter Clemens, Hamburg-Nienstedten, and Egidius Westenfelder, Hamburg-Fuhlsbuttel, Germany, assignors to Standard Oil Development Company, Elizabeth, N. J.

Application September 23, 1950; Serial No. 186,402
In Germany February 24, 1949

13 Claims. (Cl. 169—15)

1. In stationary air-foam fire-extinguishing installations for storage tanks for inflammable liquids, the air foam has to be introduced at the upper edge of the tank. Heretofore, therefore, air-foam producers, similar in form to air-jet pumps, which are fed with the mixture of water and foam-producing agent by means of horizontal and vertical liquid pipe-lines, have been mounted externally in the vicinity of the upper edge of the tank. In this known arrangement, however, there is a danger that the air-foam producer will be damaged in the event of an explosion of the tank, for example if the top of the tank is blown off. Furthermore, this method of mounting makes supervision of the air-foam producer very difficult.

The underlying problem with which the invention is concerned is to provide an air-foam producing apparatus similar in form to an air-jet pump, in which the air foam is conveyed under its own pressure over a considerable distance and/or a considerable height, and which consequently may be mounted on the ground or in the vicinity thereof. In accordance with recent requirements the air foam has to have a ratio of water to air of from 1:5 to 1:10, and in addition possess adequate stability, which is obtained, for example, by a good water-retaining power. This problem cannot be solved with the air-foam producers known heretofore. If an attempt is made to convey air-foam over considerable distances with the known apparatus, a back pressure is set up, the effect of which is that the foam flows backwards out of the air inlet openings of the air-jet pump. In contradistinction to the existing prejudice that the problem of producing and conveying air-foam over considerable distances by means of air-jet pumps is insoluble, the present invention is based on the observation that the problem can be solved if the air-jet pump is of special design and dimensions. In the known air-jet pumps employed heretofore, which in general operated with fine atomisation of the liquid jet, the greater part of the kinetic energy inherent in the liquid jet is consumed by atomisation and the work of foam mixing, so that, after leaving the foam producer, the actual foam jet possesses only a small amount of kinetic energy. For this reason, such foam-producing apparatus is not adapted to overcome a considerable back pressure in the supply pipe-line. It is, therefore, necessary to design and dimension the foam-producing apparatus so that the least possible energy is lost in the suction and mixing work of the jet and

consequently sufficient amounts of energy are available for conveying the foam.

It is an object of the invention to provide an apparatus for the production of air-foam which is conveyed under its own pressure over a considerable distance and/or a considerable height, comprising a plurality of open air-jet pumps connected in parallel which are fed from a common foam-liquid pipe-line and open into a common foam pipe-line, the jet nozzles and mixing tubes of the air-jet pumps being designed and dimensioned in such a manner that a jet of good coherence and having little tendency to scatter issues from the jet nozzle, said jet being narrowly enclosed by a mixing tube, preferably of cylindrical shape, whereby it is maintained over a considerable length without premature breaking up.

When this condition is satisfied, the energy lost through air-suction and foam-production work is reduced to a minimum. It is clear that in order to carry the principle of the invention into effect, the cross-section of the mixing tube must be in a certain ratio to the cross-section of the jet nozzle. The ratio of the cross-sections should be only slightly greater than the ratio of water to air, that is to say, as stated above, from 1:5 to 1:10.

A further object of the invention is to provide a stationary air-foam extinguishing installation for storage tanks containing inflammable liquids, which is fed by an air-foam producing apparatus of the kind set forth above, the air-foam producing apparatus being arranged on or close to the ground and preferably outside the protection wall and being connected by means of a foam ascension pipe to the foam inlet into the tank.

A form of the invention is illustrated by the accompanying drawings in which:

Fig. 1 shows a foam-producing apparatus according to the invention, in elevation;

Fig. 2 shows a foam producer according to Fig. 1, in longitudinal section in the direction II—II in Fig. 3 on a larger scale;

Fig. 3 shows a section in the direction I—I in Fig. 2;

Fig. 4 shows an air-jet pump with internal air supply on a larger scale;

Figure 5 shows diagrammatically the arrangement of a foam-extinguishing installation on a large tank;

Referring to Figs. 1 and 2, the foam-producing apparatus comprises, for example, six centrally arranged air-jet pumps 6, secured to con-

3

necting pieces 9 on the nozzle plate 1 of a liquid distributor 8. The liquid distributor widens conically in the direction of flow and is provided with fittings for reducing the resistance to flow, for example in the form of a cone 10 or streamlined body mounted in the centre of the nozzle plate 1 with its apex pointing against the direction of flow. The supply of water mixed with foaming agent may be connected to the flange 11 of the liquid distributor 8. In this case, the flange 11 may be connected directly or indirectly by means of hose-pipes to a mixing piece, not shown, which in its turn has connections for the water and foaming agent pipe-lines. The flange 11, however, may also be connected to the water supply, while the foaming agent enters through an inlet 12 and is distributed in a manner not shown. The connecting piece 13 is for the connection of a pressure gauge.

The air jet pumps 1 to 6 consist of a liquid nozzle 14, which is cylindrical in its forward part. The cylindrical part of the nozzle has a cylindrical core 15, thus providing a nozzle exit of annular cross-section. This results in a low scatter effect of the liquid jet which emerges with a large surface.

As shown in Fig. 4, the core 15 of the liquid nozzle 14 may be replaced by a tube 16, through which enters the air supplied from inside to the liquid jet issuing from the annular space 17 of the nozzle, so that intimate contact takes place between the hollow cylindrical liquid jet and the air aspirated from the outside and inside.

Secured to the nozzle plate 1 is a tube 18 or similar suitable connecting means, carrying at its other free end a plate 19 having six bore-holes in which are mounted the mixing tubes 20, carrying the air nozzles 21 projecting beyond the edge of the nozzles 14. It is essential that a separate mixing tube should be provided for each jet pump, and that the mixing tubes should run substantially parallel or converge at a slight inclination to the central axis. At their other ends, opposite to the air nozzles 21, the mixing tubes 20 are fixed in a plate forming the bottom of a foam chamber 22, which gradually tapers to the prescribed connection width of the foam pipe-lines or pouring pipes to be connected to the flange 24. As indicated in Fig. 2, a ring 25 may also be used instead of a plate, in which case the plate 19 forms the bottom of the foam chamber. A connecting piece 25 is provided for the connection of a pressure gauge.

Conveniently, the mixing tubes 20 are surrounded by a conical casing 26 with line contact. This casing 26 imparts protection and adequate strength to the apparatus. Preferably, the casing 26 is constructed so that it forms at the same time the foam chamber 23.

The operative reliability of the foam producing tubes according to the invention is substantially greater than that of the known tubes, since rebounding and reversal of flow do not occur. In addition, considerable resistances in the conveying pipe-line are overcome, such as occur for example with inadequate liquid pressure in consequence of the formation of excessively heavy foam.

Whereas in the known foam producers, a foam of high conveying pressure has been possible only with the use of pumps, and the extinguishing of a mineral oil tank of large diameter by means of air-foam has heretofore been practically impossible, it is possible by the present invention for such tanks to be rendered safe

by foam-producing tubes operating without portable pumps. In addition, the foam-producing capacity, that is to say, the effective quantity of foam produced per foam-producing tube in unit time, is substantially greater than in all the systems known heretofore. In consequence of the high foam-producing capacity, the good quality of the foam and the high foam pressure, large tanks filled with mineral oil may be provided with air-foam fire-extinguishing installations and fires may thus be extinguished, since it is possible to provide the foam-producing tubes in a stationary or mobile manner on the ground and it is not necessary to mount the foam-producing tubes on the upper edge of the tank as heretofore. This affords the advantage that, for example, adequate protection may be provided for very large storage installations with a few mobile foam-producing tubes.

As follows from Fig. 5, in using the foam-producing tubes of the invention, it is merely necessary to provide the tanks with an extinguishing pipe network 27 with rising pipes 28, which lead to the upper part of the tank 29. The connecting points 30 for the foam-producing tubes may be provided in a readily accessible manner close to the ground and outside the protection wall 31. This arrangement permits of the connection of portable foam-producing tubes at the necessary connecting points in each case.

We claim:

1. Apparatus for the production of air-foam, comprising an elongated foam delivery chamber having a discharge end and an inlet end, a foam mixing tube extended into said chamber toward the discharge end thereof, terminating in longitudinally spaced relation thereto, injector means for introducing foam forming liquid into said tube as an annular stream of such liquid, means for admitting air into said tube as a flowing stream in intimate surface contact with said annular stream of liquid, and conduit means for supplying foam forming liquid to said injector means.

2. Apparatus according to claim 1, in which said injector means comprises a jet nozzle member having a discharge end and a coaxial core element interiorly of said end, said element in radially spaced relation to said nozzle forming an annular discharge passageway.

3. An apparatus according to claim 2, in which said core element is a solid cylindrical element.

4. An apparatus according to claim 2, in which said core element is a hollow tubular pipe element opening at one end through the nozzle discharge end, the other end of said element opening outwardly through a side wall of said nozzle.

5. Apparatus for the production of air foam, comprising a foam chamber, having inlet and outlet ends respectively, a plurality of foam mixing tubes, each having an inlet end and a discharge end, extended into said chamber through the chamber inlet and disposed axially thereof in circularly spaced relation one to another, extending in the direction of the chamber outlet, with the discharge ends terminating interiorly of the chamber in substantially equidistant spaced relation to the outlet end thereof and the inlet ends opening outwardly therefrom, and conduit means for injecting foam-forming liquids into the inlet end of each foam-mixing tube as a jetted annular stream of such liquids and so as to inspirate air through said mixing tube inlet ends.

6. An apparatus according to claim 5, in which

said foam-forming chamber comprises an elongated casing member having a foam outlet end and a closure member for the opposite end of said casing and chamber, said member providing support means for the mixing tubes extended into said chamber.

7. An apparatus according to claim 5, in which said axially disposed mixing tubes extend in substantially parallel relation to each other and to the principal axis of said chamber through the outlet thereof.

8. An apparatus according to claim 5, in which said axially disposed mixing tubes extend longitudinally of said chamber in converging substantially uniformly angular relation to the principal axis of said chamber through the outlet thereof.

9. An apparatus according to claim 5, in which said conduit means for injecting foam-forming liquids into the inlet end of each foam mixing tube, comprises a conduit distributor element having an inlet portion, and an outlet end portion extended toward and terminating in spaced relation to the inlet ends of said mixing tubes, and a plurality of jet nozzle elements for discharge of said liquids, each having an inlet end communicating with said distributor element and a discharge end extended into the inlet end of a mixing tube in radially spaced relation to said tube.

10. An apparatus according to claim 9, in which said distributor element comprises a hollow, frusto-conical member having an inlet at the apex end thereof and an open base end portion, a closure plate for said base end portion, and a plurality of tubular conduit members supported by and opening through said closure, each of said members adapted to receive and communicate with a jet nozzle element for discharge of foam-forming liquids therethrough.

11. An apparatus according to claim 9, in which said distributor element comprises a conduit member flared outwardly in the direction of said mixing tube inlets providing a chambered portion in said member.

12. An apparatus according to claim 10 including a flow deflector internally of said distributor element and comprising a conical mem-

ber secured to said closure plate by its base end and concentrically therewith, the apex end of said member extending in the direction of the inlet to said distributor element.

- 5 13. Apparatus for the production of air-foam which comprises the combination of a casing defining a foam chamber, said casing having opposite inlet and outlet portions, a closure for the inlet end portion of said casing, said closure provided with a plurality of radially disposed, circumferentially spaced passageways opening therethrough into said casing, a plurality of foam-mixing tubes extended through said passageways into the casing and chamber, said tubes each having an inlet end opening exteriorly of the casing and discharge end opening into the casing and chamber, said tubes supported within said casing in spaced relation to one another circumferentially of the chamber, and arranged 10 therein with the axis of each tube in substantially equidistant radial relation to the axis of said casing, and means for supplying foam-forming liquids and air to said mixing tubes, comprising conduit means for conveying said liquid, 15 a liquid distributor member communicating with said conduit means at one end and flared outwardly therefrom toward the inlet end of said casing, a plurality of jet nozzle elements opening from said distributor member and extending 20 therefrom into the inlet ends of said mixing tubes in coaxial radially spaced relation thereto, and a concentric core element internally of each jet nozzle providing for the discharge of an annular liquid stream therefrom.
